HOUSING FOR WINDOW DRIVE OPERATOR

Lyle L. Sodeman, Clinton, Iowa, assignor to Curtis Companies Incorporated, Clinton, Iowa, a corporation of Iowa

Filed Mar. 7, 1960, Ser. No. 59,627

Term of patent 14 years

(Cl. D10—10)

Figure 1 is a perspective view of a housing for window drive operator showing my new design;

Figure 2 is a plan view of the housing shown in Figure 1;

Figure 3 is a front elevational view of the housing shown in Figure 1; and

Figure 4 is a side elevational view of the housing shown in Figure 1.

I claim:

The ornamental design for a housing for window drive operator, substantially as shown.
